UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

TYPE SETTING AND DISTRIBUTING MACHINE.

1,034,099.

Specification of Letters Patent. Patented July 30, 1912.

Application filed March 7, 1904; Serial No. 196,840. Renewed January 23, 1908. Serial No. 297,447.

To all whom it may concern:

Be it known that I, HARRY C. GAMMETER, a citizen of the United States, residing at Cleveland, in the county of Cuyahoga and State of Ohio, have invented a certain new and useful Improvement in Type Setting and Distributing Machines, of which the following is a full, clear, and exact description, reference being had to the accompanying drawings.

The object of this invention is to provide an efficient machine for rapidly producing quantities of printed matter, particularly in making many copies of circulars or letters, which shall have all the appearance of having been individually written upon the typewriter, whereby a more careful perusal of such matter by the recipient is obtained.

The present invention is an improvement on the machine shown, described and claimed in my prior Patent No. 722,404, re-issued as No. 12,622.

The complete machine, in its preferred form, comprises a supply member for containing type arranged in lines of the same letter, a printing member, transfer mechanism for conveying the type individually from either member to the other, finger keys for operating such transfer, a rotary impression platen coöperating with the printing member, means for carrying an inking ribbon between the printing member and platen, and means for feeding the paper to the impression line.

Various features are included in the present invention, among which may be mentioned: the machine as a whole; finger keys for enabling the transferring of type; the transfer mechanism itself; the indicating mechanism to show the position of the supply member; the interlocking mechanism for the supply member; and various details contributing to the efficiency and simplicity of the machine.

The construction and arrangement of the spools which carry the inking ribbon and the mechanism for holding and driving such spools herein partially shown constitute the subject matter of my Patent No. 816,311; likewise the paper feeding mechanism herein shown is covered in my Patent No. 812,735.

In the drawings, Figure 1 is a front elevation of the machine complete; Fig. 2 is

an end view partly sectional thereof; Fig. 3 is a cross section just to the left of the supply drum, being on line 3-3 of Fig. 1; Fig. 4 is a horizontal section on line 4-4 of Fig. 3; Figs. 5^a, 5^b and 5^c are horizontal sections on line 5-5 of Fig. 3, showing the transfer mechanism in different positions. Figs. 6^a and 6^b are horizontal sections on line 6-6 of Fig. 3, with the parts in different positions. Fig. 7 is a vertical section of the detail shown in Figs. 6^a and 6^b. Fig. 8 is a perspective view of the type employed. Fig. 9 is a view of the distributing follower. Fig. 10 is a sectional rear elevation of the transferring combs extending above the two drums.

The supply drum as a whole is designated A, and the printing drum B. These are arranged so that type ordinarily stored on the supply drum may be transferred as desired to the printing drum—a preferable way being that shown in the drawings wherein the drums are of the same periphery and are placed with their axes in alinement. The supply drum consists of a series of bars or rails a having enlarged and rounded outer edges and mounted longitudinally around spiders a' secured to a shaft a² which is journaled in the end member z and intermediate member z' of the general frame Z.

The printing drum B is mounted on a shaft b journaled in the intermediate frame member z' and the end member z². Into radial grooves in the periphery of this drum are set rails b' having enlarged and rounded outer edges, similar to the rails a.

The type C are in the form shown in Fig. 8 having across them holes c communicating with their feet. The type are thus adapted to be slipped endwise over the various rails and retained thereon while the drums rotate.

The rails b' do not occupy the entire periphery of the drum B, an opening b² being made in a portion of the drum. Into this opening are set a pair of spools D and D'. After the type have been assembled on the printing drum, as hereinafter explained, a ribbon from one of these spools is passed around the type and secured to the other spool. Thereafter the printing may be accomplished by rotating the drum B and drawing between it and an impression platen E the paper to be printed. The

drum is rotated by a crank F geared to the shaft b by gearing f and b². The paper is shoved by hand toward the machine along the surface of a table G, where it passes between rollers i and i' and thence between the roller i² and the impression platen E. The roller i is shown as automatically rotated to feed the paper by a rack b³ on the printing drum, which, during each rotation, meshes with a pinion i³ which is in mesh with a gear on the roller i.

I now come to the mechanism for assembling type on the printing drum from the supply drum, or distributing it from the printing drum to the supply drum, wherein the invention covered by the present application resides.

When the machine is idle, the type are carried on the rails of the supply drum, all of the type on one rail being of the same character. Between the two drums and adjacent to the uppermost portion thereof is a rotatable head N into which the type are adapted to be fed from either drum, and which is arranged to be operated to transfer it to the other drum. To bring that rail of the supply drum, which carries the desired character, in line with the transfer head, I secure to the shaft a² of the supply drum a hand knob a⁵, by which the drum may be turned, as desired. On the left-hand end spider a' of the supply drum is formed a gear a⁶. This gear meshes with an idler j which meshes with a pinion j' on a shaft J extending lengthwise of the machine above the two drums. Formed on this shaft is a steep screw-thread j₂, and with this thread engages a nut having a depending pointer j³. Adjacent to the pointer and extending lengthwise of the machine is an indication strip J' having printed on it the various characters which the supply drum carries in the order they are arranged on the supply drum and such distance apart that the pointer j³ will always be at the character on the indicator corresponding to the characters on the rail a which is in alignment with the transfer head N. Therefore, to bring the different characters into this alignment it is only necessary for the operator to grasp the knob a⁵ and turn it in one direction or the other until the pointer indicates the desired character. To cause the actual transfer of type from one drum to the other I provide a pair of keys P and P'. These are arranged to rotate the head N in one direction or the other and to cause other operations, hereinafter described, to transfer the type from one drum to the other.

I will first describe the operation of the key P to transfer the type from the supply drum to the printing drum, the operation of key P' to distribute type being substantially the same but reversed. This key P is on a lever p journaled on a hub a⁹ sur-

rounding the shaft a². The first operation of the depression of the key is by means of a depending arm p⁶ formed on the lever which forces rearward a bar V whose downturned end v, the depending arm engages. This bar is guided by the frame and normally held forward by a spring v' but when forced rearward its end enters one of a series of radial holes a⁸ formed in one of the spiders of the supply drum, and this locks that drum definitely and accurately in position. Extending upward from the lever p is an arm p' on which is formed a segmental gear p². Adjacent to this gear, but normally out of mesh therewith by reason of the teeth being omitted at the forward end of the arm p', is a pinion r on a vertical shaft R. While the rod V is being moved rearward to lock the drum, the smooth portion of the arm p' has moved past the pinion r, and thereupon the teeth p² come into engagement with that pinion, wherefore the next operation of the depression of the key P rocks the shaft R. The movement communicated by the pinion r to the shaft R normally communicates motion to the head u³ frictionally mounted on that shaft, as hereinafter explained; and to this head are secured by a pair of links u and u' the combs U and U'. The comb U stands above the supply drum and is guided by the slot and pin connection u² with a member U², which extends over onto the two sides of the comb U. This member U² has a slot and pin connection u³ with the frame member z⁴, and a spring u⁵ adjusted by a set screw u⁶ frictionally retains the member U² in place. The movement of the shaft R draws the comb U diagonally downward until its teeth engage teeth on the upper surface of a chaser S which stands just behind the type on the supply drum—one chaser on each rail. Thereafter further movement of the shaft R moves the comb U and the member U² (which has been stationary) in unison against the action of a spring u⁴ in the direction to move the chaser and the type in front of it toward the transfer head N. This movement continues until the foremost type has entered the transfer head. On the return movement of the shaft R the comb U rises diagonally backward to clear the follower and then returns with the member U² horizontally to initial position. The comb thus has a four-way or orbital movement which causes it to entirely clear the follower so that there is no chance of the follower being displaced by the comb dragging backward over it.

The transfer member N consists of a cylindrical head mounted on the rotatable shaft n³. This head has formed in it cross recesses n and n', as shown in Figs. 5^a, 5^b and 5^c. In these recesses stands a block N' of the form of a Greek cross. The front and

rear arms of this block limit its movement and the cross arm occupies the recess n , which is normally in alignment with the two drums. Now, there is space in addition to the block in this latter recess for just one type,—it being understood that the bodies of the type are all of the same size. As the foremost one of the type, being shoved forward by the comb U , enters the recess n , it shoves the block N' in advance thereof until the type is entirely within the head, as shown in Fig. 5^a. Rigid on the shaft n^3 is a mutilated pinion n^2 adapted to be engaged and driven by the mutilated pinion r' on the shaft R . The further movement of the key lever p , through these two pinions, now gives the shaft n^3 one-half a rotation. This turns the head N to bring the type therein opposite the printing drum,—this position of the parts being shown in Fig. 5^b. Extending upward from the block N' is a pin n^4 which takes into a slot in an arm t , which is rigidly secured to a sleeve T loosely surrounding the shaft R . On the lower end 25 of the sleeve is an arm t' loosely surrounding shaft n^3 and having a downwardly extending pin t^2 . An arm r^2 (preferably in the form of a leaf spring) carried by the shaft R , now engages the pin t^2 and swings 30 the arm t' and hence the arm t to shove the block N' to the right to eject the type onto the printing drum rail b' . This is the final position of the transfer head, as shown in Fig. 5^c. As the action of the comb U in advancing type is completed before the completion of the rotation of the shaft R , I provide a yielding connection between these two parts. This is shown as a slip device arranged between the shaft R and the head u^9 . Secured to the shaft R is a boss r^3 which carries a pin r^4 . Surrounding this boss is a cup-like flange u'' of the head u^9 , which flange has a notch in which the end of the pin normally seats. During the first 45 portion of the rotation of the shaft R the boss r^3 and head u^9 rotate in unison, but as soon as the foremost type is stopped by having shoved the block N' to its extreme position, the pin r^4 snubs out of the recess in the flange u'' and rides around idly in contact with that flange. A spring r^5 adjusted by screw r^6 presses the pin toward the flange. The operation of assembling the type of the printing drum is to set the drum with one of its rails b' in alignment with the center of the transfer head. Then the supply drum is rotated to bring the proper character into such alignment, and the key P is depressed to cause its transfer. This operation of turning the supply drum and depressing the key P continues alternately until a line of type is set up. Then the printing drum is turned to bring into alignment the rail on which the next line is to

be set. If the matter is to be an imitation of ordinary typewritten work, only every alternate rail on the printing drum will be used. If desired to imitate single-space work on the typewriter, consecutive rails would receive type. 70

To hold the printing drum in accurate position for the operation of setting the type, I provide a detent device L , which has a roller adapted to engage frictionally between teeth on the gear b' on the printing drum. The primary purpose of this gear is to drive the impression platen, but it is arranged with its teeth spaced the same as the rails b' . This detent may be thrown out of action when the drum is to be rotated to print by turning on itself the pin l , whose flattened end lifts up the spring l' . To feed the drum forward rail by rail, the operator simply turns the knurled head b^2 85 on a pin whose other end carries a 3-tooth pinion b^3 . The shank of the pin is triangular and on this portion bears the spring l' , preventing accidental displacement. In distributing the type from the printing drum back to the supply drum, the operation is similar but reversed. The printing drum is left stationary with a loaded rail in alignment with the transfer head. Then the supply drum is turned to bring the rail corresponding to the endmost type on the printing drum into alignment, and the key P' is depressed to cause the transfer of type by the rotation of the head N and the shifting of the block N' in the opposite direction to that caused by the key P in assembling type, as heretofore described. 90

On the printing drum there can be no chaser projecting up higher than the face of the type, and therefore for communicating the movement from the comb U' to the type I provide a somewhat different arrangement from that employed on the supply drum, namely: Slidable along the frame of the machine above the printing drum I mount a block K having a pawl k adapted to engage behind the type and another pawl k' adapted to be engaged by the comb U' , this latter pawl being pressed upward by a spring. This comb is guided by pins and slots u^7 , as shown, wherefore when drawn toward the transfer head against the force of the spring u^8 it moves downward and then forward to advance the type. The pawl k may be thrown out of action altogether by turning up the lever k^2 , which is connected to the pawl k , the friction of the latter and the block then holding it in idle position. 105

In order to allow for the easy effecting of corrections in the matter set up, I provide a rail on the supply drum which is normally empty. This rail is in advance of the rails normally loaded and is brought into alignment with the transfer head when 115 120 125

ever the drum A is turned to one extreme position, as shown in the drawing when the pointer j^s is opposite the star on the indicator. At the same time a cam a'' carried by the drum engages a roller t^s on the sleeve T and raises that sleeve, and this raises the block N' so that as much of the line as may be desired is shoved through the head onto the emergency rail. Then any wrong letters are distributed on the supply drum and new letters are set up on the printing drum and thereafter the emergency rail is brought into alignment with the head, and the matter, which was thereon, is returned to the printing drum. By this means a correction may be made in any portion of the set line without redistributing the whole line. A suitable pin (not shown) on the supply drum engages the stop z^s on the frame member z' limiting the rotation of the drum in one direction so that the emergency rail is at the end of the turn.

From the above description, it will be seen that this invention provides means whereby individual type may be conveniently and rapidly assembled in a page form and printing accomplished therefrom through a ribbon operating against a rotary impression platen. The rolling pressure given by this printing operation, together with the fact that the type are somewhat loosely held on the drum, gives a slight irregularity to the printed impression, and this, together with the fact that the printing is accomplished through an inking ribbon, enables a very close imitation of typewritten work. The arrangement of the stationary feed table along which the paper may be passed by hand until it engages the mechanism allows separate sheets to be supplied to the machine with substantially the same rapidity with which the machine may be operated. At the end of the printing operation the ribbon is removed from the type and they are quickly distributed to the supply member. The finger keys and indicating mechanism and other features shown increase the speed and accuracy of assemblage and distribution over that shown in my prior Patent No. 722,404, while the mechanism which engages each individual type during transfer prevents over-setting, due to an irregular operation, which is also a decided advantage.

It should be noted that the feature of the roller impression platen which co-operates with the type and inked fabric to produce the close imitation of type-writing described, is included in the combinations claimed in a division of this application, namely, Serial No. 531,451, filed December 4, 1909. It should also be noted that the combination of a railed rotary typeholding member with means for feeding it step by step proportionally to the rail distances, is claimed in

divisional Patent #1,015,760, issued January 23, 1912, as is also the combination with the platen of the rotary member and the step by step feeding independently of the transferring mechanism.

70

I claim:

1. In a typesetting and distributing machine, the combination of a mechanism for carrying a supply of type, a printing mechanism adapted also to carry type, means 75 for transferring individual type from either of said mechanisms to the other, and finger mechanism for operating such means, substantially as described.

2. The combination of two mechanisms 80 adapted to carry type, means for transferring type from either of said mechanisms to the other, and finger mechanism for operating such means in either direction.

3. The combination of two mechanisms 85 adapted to carry type, type transferable from either mechanism to the other, and a pair of finger keys operating to cause such transfer.

4. The combination in a unitary machine 90 of two adjacent mechanisms adapted to carry type, mechanism adapted to transfer type from the end of either mechanism to the adjacent end of the other, and finger mechanism for operating such transfer 95 mechanism.

5. The combination in a unitary structure of two type-holding mechanisms placed end to end and finger mechanism mounted between the two type-holding mechanism and 100 operating to transfer type from either of such mechanisms to the other.

6. The combination of a printing mechanism adapted to carry lines of type, a supply mechanism for such type, a transfer mechanism for conveying the type one at a time from the supply to the printing mechanism or vice versa, and finger mechanism movable independently of the supply mechanism and printing mechanism for operating said 110 transfer mechanism in one direction or the other.

7. The combination of a pair of members adapted to carry type, a movable transfer device, mechanism for feeding type from one 115 of said members to said device, for then moving said device, and for then moving the type from said device to the other member, and a finger key arranged to cause such three operations at one actuation thereof. 120

8. The combination of supply mechanism, printing mechanism, a finger key for transferring type from the supply to the printing mechanisms, a finger key for transferring type from the printing mechanism to the 125 supply, and means for independently moving each of said mechanisms.

9. The combination of supply mechanism, printing mechanism, means for feeding type from either of said mechanisms to the other 130

- and a pair of finger keys for operating such means.
10. In a type setting and distributing machine, the combination of a pair of members each adapted to carry type, a transfer device, mechanism for feeding type in either of said members to the transfer device, mechanism for operating the transfer device, and finger mechanism for operating the mechanisms mentioned.
11. The combination of mechanism for carrying a supply of type, printing mechanism adapted also to carry type, feeding mechanism to advance the type in either the supply mechanism or the printing mechanism toward the other, an oscillatable operating means to drive the feeding mechanism, and finger operated mechanism for oscillating said operating means in either direction to feed the type accordingly.
12. In a combined typesetting, printing and distributing machine, the combination with the supply mechanism and the printing mechanism, of a pair of finger keys, one for setting and one for distributing.
13. In a typesetting and distributing machine, the combination of a printing drum adapted to carry lines of type, a supply mechanism for such type, a transfer mechanism for conveying the type from the supply to the printing drum, or vice versa, a pair of finger keys for operating said transfer mechanism in one direction or the other, substantially as described.
14. In a typesetting and distributing machine, the combination of a pair of drums, each adapted to carry type, a transfer mechanism adapted to convey type from either drum to the other, and a pair of finger keys adapted to operate said transfer mechanism, one in one direction and the other in the other direction, substantially as described.
15. In a typesetting and distributing machine, the combination of a pair of drums placed end to end and each adapted to carry type, transfer mechanism adapted to convey type from the end of either drum to the adjacent end of the other, and a pair of finger keys adapted to operate said transfer mechanism, one in one direction and the other in the other direction.
16. The combination of a rotatable printing drum and a rotatable supply drum, each adapted to carry rows of type, means between the drums adapted to receive type one at a time from either of the drums, means for moving such type from one drum to the other, and finger mechanism for operating said last-mentioned means, substantially as described.
17. The combination of a pair of drums, each adapted to carry type, type-controlling mechanism between the same, a finger key for operating said controlling mechanism, and mechanism operated by said finger key for feeding the type from one of said drums to the controlling mechanism.
18. In a typesetting and distributing machine, the combination of a pair of drums, transfer mechanism, and a pair of finger keys for operating said transfer mechanism in opposite directions, substantially as described.
19. In a typesetting and distributing machine, the combination of a pair of drums, each adapted to carry type, a transfer mechanism adapted to convey type from either drum to the other, a pair of finger keys one adapted to operate said transfer mechanism in one direction and the other in the other direction, and means for rotating said two drums independently, substantially as described.
20. The combination of a pair of type drums placed end to end, mechanism for transferring individual type from either to the other, and a pair of finger keys for operating said transfer mechanism in opposite directions.
21. The combination of a pair of type drums, a pair of finger keys, mechanism adapted to be actuated by said keys to transfer type between the drums, means for rotating each drum, and means for holding the drums against rotation during the transfer.
22. The combination of a supply drum and a printing drum, each adapted to carry type, a transfer mechanism adapted to convey type from the supply drum to the printing drum, a finger key adapted to operate said transfer mechanism, means for rotating said two drums independently, and means operated whenever said finger key is operated for locking said supply drum.
23. Two type holders, finger keys, and mechanism operated thereby for transferring type from either holder to the other.
24. The combination of a printing member adapted to carry individual type, keys accessible for finger contact, and mechanism operated thereby for assembling type on the printing member and distributing assembled type.
25. The combination of a rotary printing drum adapted to carry individual type, finger keys, and mechanism operated thereby for assembling type for the printing drum or distributing assembled type.
26. The combination of a type storage member, a rotary printing drum, mechanism intermediate of the storage member and the printing drum, finger keys, and mechanism operated thereby to transfer individual character type one at a time from the storage member to the printing drum via the intermediate mechanism and vice versa.
27. The combination, in a unitary machine, of a member of a printing couple formed to carry a plurality of printing lines,

a key accessible for finger depression, and mechanism operated by such depression for assembling type directly on the couple.

28. In an assembling machine, the combination of a rotary drum, a key accessible for finger depression at the front of the machine, and mechanism operated thereby for assembling type in parallel lines on the drum.

29. The combination, in a unitary structure, of two typeholding mechanisms placed end to end, mechanism mounted between the two typeholding mechanisms and operating to transfer type between them, and finger keys for actuating such intermediate mechanism.

30. The combination of a rotatable printing drum and a rotatable supply drum, each adapted to carry rows of type, means between the drums adapted to receive type one at a time from either of the drums, mechanism for transferring such type from one drum to the other, and finger keys accessible at the front of the machine for operating said transfer mechanism.

31. The combination of a printing drum, means for rotating the printing drum continuously, means for temporarily holding the printing drum stationary, and finger keys for assembling type on said drum or distributing therefrom when so held.

32. The combination of two rotary members each adapted to carry type, mechanism for transferring individual type from one member to the other and assembling a plurality of such type thereon, and a finger key actuatable independently of the movement of either member and adapted to operate the transfer mechanism.

33. The combination of a rotary typeholding member, means for rotating it continuously, means for temporarily holding it against rotation, a depressible key accessible for finger operation, and mechanism actuated thereby for assembling type on the said member.

34. In a combined typesetting, printing and distributing machine, the combination with a supply mechanism and printing mechanism, of mechanism for assembling and distributing, and finger keys for operating such mechanism last mentioned.

35. The combination, in a unitary machine, of a movable type carrying and printing member, mechanism for assembling type on said member, and a depressible key accessible for finger contact for operating said mechanism.

36. The combination with a printing member, a type storage member, assemblage and distributing mechanism to transfer type from either member to the other, said mechanism being key-operated and movable in one direction to assemble and the other to distribute.

37. The combination, with a printing mem-

ber, of a type storage member, mechanism for transferring a plurality of type from one of said members into a single line of the other member, and a key accessible for finger operation and adapted to operate said mechanism independently of the movement of either member.

38. The combination of a pair of rotary typeholding members placed end to end, mechanism for transferring individual type from either to the other, and finger mechanism operated independently of the movement of either rotary member for controlling the transfer mechanism.

39. The combination of a pair of members each having longitudinal parallel rails providing type channels, mechanism for transferring type from a channel of one member to a channel of the other, and a finger key adapted to be operated independently of the movement of either member and adapted to operate such transfer mechanism.

40. The combination of a type-carrying member provided with overhanging rails adapted to loosely and individually hold grooved type, a typeholder, mechanism for shoving such type from said holder lengthwise of the rails onto said type-carrying member, and a finger key actuatable independently of the movement of said typeholder for controlling such mechanism.

41. The combination of a printing member having parallel overhanging rails adapted to loosely hold grooved individual type, a storage member adapted to confine such type, mechanism for transferring the type from the storage member to the printing member and vice versa, and finger keys for controlling such operation.

42. In a duplicating machine, the combination, with printing mechanism, of supply mechanism, means for advancing a line of type from either mechanism toward the other by shoving on the rear end of such line, and means engaging the individual type at the forward end of such line for limiting such advancement to one type at a time.

43. The combination with the two members of a printing couple, of means for feeding type to or from one of said members and means engaging the foremost type for limiting the feed to one type at a time.

44. The combination of means for holding a line of type, means for feeding such line as a whole in the direction of its length, movable mechanism adapted to temporarily limit the feed to one type at a time, and means for giving said movable mechanism a movement to get it out of the path of the foremost type to enable farther advancement of such foremost type in the direction of the length of the line past the mechanism.

45. The combination, with type uniformly dimensioned crosswise, of a holder

adapted to hold a line of such type, means for feeding such line of type, movable mechanism temporarily engaging individual type in the line for limiting the feed to 5 one type at a time, and means for giving said movable mechanism a movement to free the foremost type, and an aligned receiver enabling farther advancement of such foremost type in the direction of the length of 10 the line past the mechanism.

46. The combination of means for shoving forward a compact line of type, shiftable mechanism for successively engaging individuals of such line to limit the forward 15 movement, and means for giving such shiftable mechanism an additional movement to get behind each type successively and enable the farther advancement thereof.

47. The combination, with type storing 20 and printing means, of a font of type the individuals of which have the same width, means for advancing the type, and means for engaging type and movable in substantially the same direction as the advancing 25 type a distance limited to the thickness of one type and returning to initial position for each type.

48. The combination of means for holding 30 a line of type, means for advancing such line as a whole in either direction, and movable mechanism for successively engaging individual type being assembled into a line or distributed from a line to limit the feed to one type at a time.

49. The combination of two type carrying 35 members, means for transferring individual type from either member to the other, and limiting means for engaging such individual type after it has left one member and before 40 it enters the other.

50. The combination of two type carrying 45 members, means for bringing them into alignment, means for transferring type from either to the other a type at a time, and limiting mechanism engaging individual type at intermediate positions in the whole line across said two members.

51. The combination of two type holders, 50 type transferable between them, means for transferring such type from either to the other, and limiting means adapted to engage and limit the movement of each individual type.

52. The combination of two mechanisms 55 each adapted to carry a plurality of rows of individual type, means for shoving a row of type on either mechanism toward the other, and means for engaging each foremost type in such shoved row and controlling its transfer to the corresponding row of the other mechanism.

53. The combination of two mechanisms 60 each adapted to carry a plurality of rows of individual type, means for changing the

mutual presentation of the rows of the two 65 mechanisms, means for shoving a row of type on either mechanism toward the other, and means for engaging each foremost type in such shoved row and controlling its transfer to the corresponding row of the other 70 mechanism.

54. The combination of two mechanisms adapted to carry type, means for moving type from either of said mechanisms to the other, means for engaging the individual 75 type being moved, and finger mechanism for operating both of said means.

55. The combination of means for holding 80 a line of type, means for advancing it, means for limiting the advancement to one type at a time, and a finger key adapted to operate both the advancing and limiting means.

56. The combination, with means for holding 85 a line of type and means for advancing it, of a movable member which the foremost type temporarily engages, said movable member having a limited movement, another holder adapted to receive the type after disengagement from the movable member, 90 means for alining both the type holders at the time of transfer, a finger key, and mechanism controlled thereby for getting the movable member onto the rear side of the 95 foremost type.

57. The combination of supply mechanism, printing mechanism, means for feeding type from either of said mechanisms to the other, finger mechanism for operating such means, and mechanism for limiting the 100 feed to one type at a time.

58. The combination of a horizontal type holder, means for positively advancing a line of type therein, movable means engaging successive type individually to limit the 105 advancement, a horizontal type receiver into which the movable means is adapted to discharge type, and a finger key for controlling said movable means.

59. The combination of a type holder, 110 means for advancing a line of type therein, movable mechanism adapted to temporarily engage successive type for limiting the advancement, and a finger key for operating the advancing means.

60. The combination of a type holder, means for advancing a line of type therein, 115 movable means adapted to temporarily engage successive foremost type in the line to limit the advancement, means for giving said movable means a movement to free the foremost type, and a finger key for operating both the advancing and limiting means.

61. In a combined assembling or distributing and printing mechanism, the combination of feeding means, movable means for successively engaging individual type and 125

thereby limiting the feed, finger mechanism for controlling such movable means, and a printing couple onto which said feed may take place.

62. The combination of a type-holding member, means for feeding type toward or from the same, means for limiting the feed to one type at a time, and a finger key adapted to operate both the feeding and limiting 10 means.

63. The combination of supply mechanism, printing mechanism, means for feeding type from either of said mechanisms to the other, finger mechanism for operating 15 such means, and mechanism for limiting the feed to one type at a time, said last-mentioned mechanism being also operated by said finger mechanism.

64. The combination with type-storing 20 means, and printing means, of mechanism adapted to engage individual type fed from either of said means and present it to the other of said means, and a pair of finger keys adapted to operate said engaging 25 means.

65. The combination of a line of type, a follower therefor, means adapted to engage the follower to periodically advance type, coöperating means having a limited movement and adapted to engage the type singly 30 at the forward end of the line, thereby preventing undue advancement by momentum, and finger mechanism for operating such co-operating means.

66. The combination with a holder for a line of type, a follower for the type, feeding mechanism adapted to engage the follower, limiting mechanism adapted to engage each 40 foremost type, and finger mechanism adapted to operate both of the mechanisms mentioned.

67. The combination with a holder for a line of type, a follower for the type, feeding mechanism adapted to engage the follower, 45 lower, limiting mechanism adapted to engage each foremost type and limit the advancement, said limiting mechanism having a movement to allow a controlled advancement of the type, and means for giving said limiting mechanism another movement to get it out of the path of the foremost type, enabling farther advancement of such foremost type away from the limiting member.

68. The combination of a type holder, a follower for the type therein, a comb, mechanism for moving the comb to advance the follower, and movable mechanism adapted 50 to engage each type temporarily and limit the advancement.

69. The combination of a printing drum and a supply drum each adapted to carry type, said two drums having at least one longitudinal line in alinement, and mechanism operating between the drums and 65

adapted to control the type in its passage from either drum to the other.

70. The combination of two mechanisms each adapted to carry a plurality of rows of individual type, means for changing the 70 mutual presentation of the rows of the two mechanisms, means for shoving a row of type on either mechanism toward the other, means for engaging each foremost type in such shoved row and controlling its transfer to the corresponding row of the other mechanism, and finger keys for operating the shoving and engaging means. 75

71. The combination of a pair of members each provided with parallel overhanging rails adapted to loosely hold lines of grooved individual type, means for moving one of said members with reference to the other, means for transferring type from one member to the other, and a key accessible for 80 finger operation and adapted to operate the transfer mechanism independently of the movement of either member.

72. The combination of a pair of type-holding members, a movable type support, 90 means for moving type from either member to the support, and means for moving the support.

73. The combination of a pair of type-holding members, a movable type support, 95 means for advancing a line of type in either member toward the support to cause the forward type of such line to pass onto the support, means for moving the support to present such type to the other member, and means for discharging the type from such support to such other member. 100

74. The combination of a supply member, a printing member, each applied to carry rows of type, a movable type support, 105 means for feeding type from one of said members onto said support and from said support to the other member, and means for intermediately moving said support.

75. The combination of a pair of drums 110 placed end to end and each adapted to carry type, a movable type support between them, mechanism for feeding type from one of said drums onto said support, for then moving the support and for then moving 115 the type from said support to the other drum, substantially as described.

76. The combination of a supply member, a printing member, each adapted to carry individual type, a movable type support, 120 means for moving type from either member to the support, for moving the support, and for moving type from the support to the other member.

77. In a type setting and distributing machine, the combination of a pair of drums, each adapted to carry type, a movable transfer member, mechanism for feeding type in either of said drums into the transfer member and for moving the transfer member. 125 130

78. The combination of two type-holding members each having a plurality of type holders, a type support, means for causing it to align with various holders of either 5 member, means for feeding type from any of such holders onto said support and from said support to a holder of the other member, and means for moving said support intermediately of the feeding onto it and off 10 of it.

79. The combination in a unitary machine, of a supply member, a printing member, a movable type support, means for feeding type from the supply onto the support, 15 means for moving the support, and means for feeding type from the support onto the printing member.

80. The combination with a supply of type, of a printing member adapted to carry 20 parallel lines thereof, a movable type support, and means for feeding type from the printing member onto the support and for moving the support and for feeding type from the support to the supply.

81. The combination of a type supply member, a printing member adapted to carry parallel lines of type, a movable intermediate type support, means for feeding type from the supply member onto the support, 25 for moving the support and for feeding the type from the support to the printing member, and a finger key for actuating said means.

82. The combination, with a supply member, of a printing member having a plurality of parallel typeholding rails whereby lines of type may be individually and loosely held, a type support co-operating with both of said members, finger keys for feeding type from 35 either member to the support and from the support to the other member, and means for holding an inked fabric against type on the rails, said means allowing removal of the fabric to enable assemblage and distribution.

83. The combination, with type-storing means and printing means, of mechanism adapted to engage individual type fed from either of said means and turn such type around and present it facing in another 45 direction to the other of said means.

84. The combination of a pair of type-holding members, a rotatable type-supporting device, means for feeding type from either of said members to said device, for 55 rotating said device, and feeding type therefrom to the other member.

85. In a typesetting and distributing machine, the combination of a printing drum and a supply drum, each adapted to carry type, a transfer mechanism adapted to receive type from one of the drums, turn it half way around and deliver it to the other, and a finger key for operating said transfer mechanism, substantially as described.

86. In a typesetting and distributing ma-

chine, the combination of a pair of drums, each adapted to carry type, a transfer head between the same, a finger key for operating said transfer head, and mechanism operated by said finger key for feeding the type from 70 one of said drums into the transfer head, substantially as described.

87. In a typesetting and distributing machine, a pair of drums each adapted to carry type, a rotatable head between them, mechanism for feeding type from one of said drums into said head, for then rotating the head, and for then moving the type from 75 said head to the other drum, substantially as described.

88. In a typesetting and distributing machine, a pair of drums each adapted to carry type, a rotatable head between them, mechanism for feeding type from one of said drums into said head, for then rotating 85 the head, and for then moving the type from said head to the other drum, and a finger key arranged to cause such three operations at one actuation thereof, substantially as described.

89. In a typesetting and distributing machine, the combination of a printing drum and a supply drum, each adapted to carry type, said two drums having at least one longitudinal line in alinement, and a transfer mechanism adapted to receive type from one drum, turn it half way around and deliver it to the other, substantially as described.

90. The combination of a rotatable member having a groove therein and a block partially occupying said groove, mechanism for rotating said member and shifting said block therein, means for feeding type into the space in said groove, and means for receiving it when said block moves it therefrom, substantially as described.

91. The combination with means for carrying a supply of type, of the printing drum, a movable member having a groove in it, a block occupying said groove, but leaving space within the groove beyond it, mechanism for moving type from the supply into the space in the groove in front of the block, mechanism for then moving the head to present said space in different position, mechanism for then moving the block in the head to shove the type therefrom, and a finger key for operating said three mechanisms.

92. The combination, of a supply drum and a printing drum placed end to end, a rotatable head between the drums, a movable block carried thereby, mechanism for moving type from either drum into position 125 in front of the block, mechanism for then rotating the head, mechanism for then moving the block in the head to shove the type therefrom into the other drum, and a pair of finger keys each adapted to operate said 130

three mechanisms,—one in one direction and the other in the other.

93. The combination, with means for carrying a supply of type, of a printing drum, a rotatable head, a movable block carried thereby, mechanism for moving type from the supply into position in front of the block, mechanism for then rotating the head, mechanism for then moving the block in 10 the head to shove the type therefrom, substantially as described.

94. In a typesetting and distributing machine, the combination of a rotatable head having a groove therein and a block 15 partially occupying said groove, a finger key, mechanism operated thereby to rotate said head and move said block therein, means for feeding type into the space in said groove, and means for receiving it 20 when said block moves it therefrom, substantially as described.

95. The combination, with means for carrying a supply of type, of the printing drum, a rotatable head having a groove in 25 it, a block occupying said groove but leaving space within the groove beyond it, mechanism for moving type from the supply into the space in the groove in front of the block, mechanism for then rotating the 30 head, mechanism for then moving the block in the head to shove the type therefrom, and a unitary finger key for operating said three mechanisms successively, substantially as described.

96. The combination of two type-holders, and mechanism adapted to receive type from one and present it to the other facing in the opposite direction.

97. The combination of two members each 40 having a plurality of type-holders, a type support, means for causing it to align with various holders of either member, means for feeding type from any of such holders onto said support and from said support to the 45 holder of the other member, and means for causing said support to turn the type between "on" and "off" feed.

98. The combination of a supply member, a printing member, and movable mechanism 50 adapted to receive type from either member and present it to the other facing in another direction.

99. The combination of a type holder, a follower, a comb adapted to engage at various points with the follower, and a finger key for moving the comb in an orbital path.

100. In a machine of the class described, the combination of means for loosely holding a row of type, a follower therefor, a 60 comb adapted to engage the follower, a longitudinally movable member, means connecting the comb and said member to allow independent transverse movement of the comb, and means for causing movements 65 first of the comb toward the follower, then

of the comb and member with the follower, then of the comb away from the follower, then of the comb and member to initial position.

101. The combination of means for holding a line of type, a follower therefor, a comb, a movable support for the comb guided to move in a path parallel with the type, the comb having a diagonal sliding connection with said support whereby the 70 comb has an orbital movement to engage the follower, advance it, clear the follower, and return in a different but parallel path. 75

102. The combination of a type holder, a follower, and a compound driving member 80 therefor composed of two movable members, one movable on the other and also partaking of the other's movement, whereby said compound member is adapted to move toward the follower in one path and away 85 from it in another to engage and clear the follower.

103. The combination of a mechanism adapted to carry rows of type, a follower for the type, a comb adapted to engage such 90 follower, a finger key, and mechanism connecting it with the comb whereby the actuation of the finger key moves the comb toward the follower and forward.

104. In a typesetting and distributing 95 machine, the combination of a drum adapted to carry rows of type on its surface, a follower for the type, a comb adapted to engage such follower, a finger key, and mechanism connecting it with the comb 100 whereby the actuation of the finger key moves the comb downward and forward, substantially as described.

105. In a typesetting and distributing machine, in combination, a pair of drums 105 adapted to carry longitudinal rows of type in alignment, a follower behind the type in one drum, a follower suitably guided parallel with the surface of the other drum, a pair of toothed racks adapted to advance 110 said followers respectively, and finger keys for operating said racks, substantially as described.

106. The combination of a pair of drums placed end to end and adapted to carry longitudinal rows of type in alignment, followers for such type, a pair of toothed racks adapted to advance said followers respectively, and finger keys for operating said racks. 115

107. The combination of a pair of drums placed end to end and adapted to carry longitudinal rows of type in alignment, followers for such type to feed a line of type in either drum toward the other, mechanism between the two drums for limiting the advancement to a single type at a time, a pair of toothed racks adapted to advance said followers respectively, and finger keys for operating said racks and mechanism. 120 125 130

108. The combination with a pair of drums mounted end to end, a pair of combs located parallel with and adjacent to the two drums respectively, a frame member between the drums, key-operated mechanism on the frame member, and connecting mechanism between the key-operated mechanism and the combs. 65
109. The combination with mechanism adapted to carry rows of individual type, a follower supported on a guide parallel with such rows, a pawl carried by the follower for engaging the type, a comb adapted to engage the follower, and means for operating the comb. 70
110. The combination of mechanism adapted to carry rows of type, a follower for the type guided parallel with said rows, a pawl on the follower adapted to be positioned to engage or clear the type, and means for advancing said follower. 75
111. In a typesetting and distributing machine, the combination of a drum adapted to carry rows of type on its surface, a follower supported on a guide parallel with the drum, a pawl carried by the follower for engaging the type, a second pawl carried by the follower adapted to be engaged by said comb, and means for operating the comb, substantially as described. 80
112. In a typesetting and distributing machine, the combination of a drum adapted to carry rows of type on its surface, a follower supported on a guide parallel with the drum, a pawl carried by the follower adapted to engage type on the drum, a comb, a second pawl carried by the follower adapted to be engaged by said comb, means for operating the comb, and a handle carried by the follower for moving the type-engaging pawl out of action, substantially as described. 85
113. The combination of a rotatable drum adapted to carry rows of type on its surface, a follower supported on a guide parallel with the drum, a pawl carried by the follower for engaging the type, a comb adapted to engage said follower and a finger key for operating the comb. 90
114. The combination in a typesetting and distributing machine, of a drum adapted to carry rows of type on its surface, a follower supported on a guide parallel with the drum, a pawl carried by the follower for engaging type on the drum, a comb adapted to engage the follower, and means for operating the comb. 95
115. The combination of a rotary drum adapted to hold longitudinal rows of type, a follower guided parallel therewith and adjacent to the surface thereof, a pawl pivoted on the follower and adapted to act on type in an adjacent row, an arm connected with the pawl for turning said pawl on its pivot to clear the type, and means for advancing the follower. 100
116. The combination of a type-holder, a follower guided parallel therewith and having a movable pawl adapted to either engage or clear the type, and a comb for operating the follower. 105
117. The combination of a type-holder, a follower guided parallel therewith and having a movable pawl adapted to engage or clear the type, and a finger key and connecting mechanism for operating the follower. 110
118. The combination of a supply member, a printing member, mechanism for feeding the type from one of said members to the other, mechanism for engaging the type to control such feed, and a finger key for actuating said feeding and engaging mechanisms, there being a slip connector in the mechanism for causing one of such movements. 115
119. In a typesetting and distributing machine, in combination, a supply drum, a printing drum, a transfer member, mechanism for feeding the type from one of said drums to the transfer member, mechanism for then rotating said transfer member, a finger key for causing said feeding and rotating movements, there being a slip connection in the mechanism for causing one of such movements, substantially as described. 120
120. The combination of a supply member, a printing member, a type-feeding mechanism, operating mechanism for the feeding mechanism, and a yielding connection between the two mechanisms last mentioned. 125
121. The combination of two type-holding members, type-feeding mechanism, a finger key for controlling the same, and a yielding connection between movable parts of said mechanism. 130
122. The combination of two type-holding members, type-feeding mechanism, limiting mechanism to engage individual type to control the feed, operating mechanism for both the type feed and the limiting mechanism, and a yielding connection in the operating mechanism. 135
123. The combination of a supply drum, a printing member, type-feeding mechanism, a finger key for operating the same, and a yielding connection in said mechanism between the finger key and the type-engaging portion of said mechanism. 140
124. In a duplicating machine, the combination with printing mechanism, a supply mechanism, means for transferring type from one mechanism to the other, and an interlock between such transferring means and the supply mechanism. 145
125. The combination of a pair of type-holding members, mechanism for feeding type from one member to the other, a finger

key for operating such mechanism, and a locking device for one of the members, which device coöperates with said key.

126. The combination of a pair of independently movable type-holding members, mechanism for feeding type from either member to the other, finger mechanism for operating such feeding mechanism, and means preventing movement of one of the type-holding members when the finger mechanism is operating.

127. The combination of a pair of independently movable type-holding members, mechanism for feeding type from either member to the other, finger mechanism for operating such feeding mechanism, means preventing movement of one of the type-holding members when the finger mechanism is operating, and means for continuously holding the other member against movement during several actuations of the finger mechanism and movement of the released type-holding member.

128. The combination of a pair of movable type-holding members, means for transferring type from either to the other, means for locking one of the members for each type transferred, and means for holding the other member for each line of type transferred.

129. In a typesetting and distributing machine, the combination of a pair of drums, mechanism for transferring type from one drum to the other, a key for operating such mechanism, and a locking device for one of the drums operated by said key, substantially as described.

130. In a typesetting and distributing machine, the combination of a pair of drums, mechanism for transferring type from one drum to the other, a key lever for operating such mechanism, a locking pin adapted to enter recesses in one of said drums, an arm on said lever and a connection between it and said pin, substantially as described.

131. The combination of a pair of rotatable type-holding drums which carry the type in longitudinal rows, means for advancing a row of type in either member toward the other a distance equal to the thickness of a type to cause transference of type one at a time, means for locking one of the members for each type transferred, and means for holding the other member for each line of type transferred.

132. The combination of a pair of drums, mechanism for transferring type from one drum to the other, a movable locking member adapted to enter recesses in one of said drums, said drum being devoid of lateral movement, and a lever for operating said member.

133. The combination of a pair of typeholding drums placed end to end, a frame member between said drums, type-transferring mechanism including finger-operat-

ing mechanism mounted on said frame member, and means coöperating with said operating mechanism to lock one of the drums.

134. The combination of a supply member, a printing member, each adapted to hold rows of individual type, mechanism for transferring type a character at a time from the supply member to the printing member, including means adapted to engage the type between the members and control the transfer, and a typeholder carried by the supply member and adapted to receive any portion of a line previously transferred to the printing member.

135. The combination of a pair of typeholding members, transfer mechanism adapted to convey the type a character at a time from one member to the other, limiting mechanism to engage the foremost type and prevent over-transfer, means for rendering the same idle, and a holder adapted to receive any portion of a line from one of the members while the limiting mechanism is idle.

136. In a typesetting and distributing machine, in combination, a supply drum, a printing drum, transfer mechanism for transferring type a character at a time, from the supply drum to the printing drum, an emergency member carried by the supply drum and adapted to receive any portion of a line previously transferred to the printing drum, and mechanism for automatically throwing out of action when the emergency member is brought into operative position the portion of the transfer mechanism which limits the transfer to single characters, substantially as described.

137. The combination of a supply drum, a printing member, mechanism for feeding type from one to the other, means for engaging individual type for limiting the feed to one type at a time, and means whereby whole lines or portions thereof may be transferred independently of the limiting mechanism.

138. The combination of a typeholder having a plurality of channels, another typeholder adapted to receive type therefrom, one of said typeholders being movable with reference to the other, a screw shaft, mechanism operatively connecting it with the movable typeholder, a pointer connected with the thread of the shaft, and an indicator with which the pointer coöperates.

139. The combination of a rotatable screw shaft, a pointer connected with the thread thereof, a chart with which the pointer coöperates, a holder for individual type, and movable means connected with the shaft for positioning the pointer according to characters of type in the holder.

140. The combination of a movable typeholding member, a rotatable screw shaft operatively connected therewith, a pointer con-

nected with the thread of the shaft, and a chart with which the pointer coöperates.

141. The combination of a rotary type-holding drum, a screw shaft geared therewith, a pointer connected with the thread of the shaft, and a coöperating chart parallel with the screw shaft.

142. In a typesetting and distributing machine, the combination with a supply 10 drum and a printing drum, the supply drum being adapted to be turned to bring different characters into transferring position, of an indicator and a pointer adapted to travel along the same, an operating connection between said pointer and supply 15 drum, substantially as described.

143. In a typesetting and distributing machine, the combination of a pair of drums adapted to carry type, an indicator 20 extending lengthwise of the machine adjacent to said drums, a pointer, a screw shaft for operating said pointer, and gearing between said screw shaft and one of the drums, substantially as described.

144. In a typesetting and distributing machine, the combination of a pair of drums placed in alinement, transfer mechanism between them, an indicator extending lengthwise of the machine, a screw shaft 30 parallel with the indicator, a pointer threaded on the screw shaft, gearing connecting said screw shaft with the supply drum, characters on the indicator being arranged in the same order as the type characters on the supply drum, and the pointer being so located as to indicate the characters on the supply drum which is opposite the transfer mechanism, substantially as described.

145. The combination of a pair of drums adapted to carry type, an indicator extended lengthwise of the machine adjacent to said drums, a pointer, and operating means connecting said pointer with one of the 45 drums.

146. The combination of a pair of drums placed end to end in alinement, a type support between them, an indicator extending lengthwise of the machine, a pointer guided 50 to travel parallel with the indicator, an operative connection between said pointer and the supply drum, characters on the indicator being arranged in the same order as the type characters on the supply drum, and the pointer being so located as to indicate 55 the character on the supply drum which is opposite said type support.

147. In a machine of the character described, the combination of a frame having 60 three upright rigid plates, a supply drum between two of said plates, a printing drum

between the other side of one of said two plates and the remaining plate, shafts carried by said plates on which the drums are mounted, means respectively beyond the 65 outer sides of the extreme plates for independently rotating the two shafts, and mechanism for transferring type from either drum to the other.

148. In a machine of the character described, the combination of a supply member, a printing member, an intermediate frame member, a finger key on the latter, and type-transferring mechanism actuated by the finger key.

149. In a machine of the character described, the combination of a frame having three upright rigid plates mounted in alinement, a supply drum between the intermediate plate and one of the end plates, a 80 printing drum between the intermediate plate and the other one of the end plates, a finger key on the intermediate plate, and type-transferring mechanism operated thereby.

150. The combination of a pair of type-holding drums, mechanism for transferring type from one to the other, a frame member between the drums, and finger mechanism mounted on the frame member for actuating 90 the mechanism first mentioned.

151. The combination of a pair of type-holding drums, mechanism for transferring type from one to the other, a frame member between the drums, mechanism mounted on 95 the frame member for operating the transferring means, and finger keys accessible at the front of the machine for actuating the mechanism last mentioned.

152. In a machine of the character described, the combination of a frame having two end plates and an intermediate plate, a supply drum and a printing drum mounted end to end between the end plates and on opposite sides of the intermediate plate, independent rotators for the two drums on the outer sides of the adjacent end plates, respectively, and finger-operated mechanism mounted in part on the intermediate plate for controlling transfer of type from either 105 drum to the other.

153. The combination of means for holding a line of type, means for advancing the same, a rock shaft for operating said means, and finger keys adapted to swing said rock 110 shaft in one direction or the other.

In testimony whereof, I hereunto affix my signature in the presence of two witnesses:

HARRY C. GAMMETER.
